UNITED STATES PATENT OFFICE.

JOHN O. CARREY, OF ST. LOUIS, MISSOURI, ASSIGNOR TO CARREY-MORSE ENGINEERING COMPANY, OF ST. LOUIS, MISSOURI, A CORPORATION OF MISSOURI.

REFRIGERATOR.

Application filed December 31, 1924. Serial No. 759,088.

This invention relates to new and useful improvements in refrigerators of the type employing compressible refrigerant fluid for cooling the refrigerator.

6 The objects of the invention are to mount the condensing coil of the refrigerating apparatus adjacent to the rear wall of the refrigerator and to provide a reservoir arranged below the condenser and preferably 10 under the bottom of the refrigerator and connected to the lower end of the condenser, said reservoir being connected to the cooling or expansion coil of the refrigerator whereby 15 a uniform flow of refrigerant to the expansion coil is thus assured.

Still further objects of the invention are to arrange the coils of the condenser in a vertical plane between and spaced from two walls whereby circulation of air is induced 20 through said space and assists in cooling the refrigerant fluid flowing through said condenser coils.

With these and other objects in view, my invention consists in certain novel features 25 of construction and arrangement of parts, hereinafter more fully described and claimed, and illustrated in the accompanying drawings, in which—

Figure 1 is a rear elevational view of the 30 refrigerator with the auxiliary rear wall thereof partly broken away.

Figure 2 is a fragmental vertical cross section taken on lines 2—2 of Figure 1.

Figure 3 is a longitudinal cross section 35 taken through the reservoir member.

Figure 4 is a transverse vertical cross section taken on lines 4—4 of Figure 3.

Figure 5 is a horizontal cross section taken on lines 5—5 of Figure 2.

40 Figure 6 is a vertical cross section taken on lines 6—6 of Figure 5.

Figure 7 is an enlarged cross section taken longitudinally through one end of the reservoir.

45 Figure 8 is an enlarged cross section taken longitudinally through the other end of said reservoir.

Figure 9 is a fragmental horizontal cross section of a modified form of refrigerator.

50 Figure 10 is a fragmental horizontal cross section of another modified form.

Referring by numerals to the accompanying drawings, 10 indicates a refrigerator which is equipped with a cooling tank 11 containing an expansion coil 12. A com-

pressor 14 is preferably located on top of the refrigerator and has its intake port connected to the discharge end of the cooling coil 12 while the outlet port of said compressor is connected to the upper end of a 60 condenser 15. The coils of condenser 15 are arranged in a vertical plane and are disposed adjacent to the rear wall 10^a of refrigerator 10. The condenser coils are seated in coinciding notches or seats formed in co- 65 operating bars or cleats 16 and 17 which are arranged in pairs and are clamped together by suitable fastening means 18 and maintain said coils in position. Bars 16 are secured to the rear wall 10^a by screws or other fastening means 19 and space said coils from 70 said wall. A pad 20, of rubber or fiber or similar material, is interposed between the rear wall 10^a and each bar 16 and insulates the coils and eliminates vibration thereof. 75 Bars 17 overlie bars 16 and are provided with pads 17^a which provide a surface bearing for a sheet or auxiliary wall 21 which is spaced from wall 10^a and condenser 15 and has its side edges 22 bent laterally to 80 bear against the wall 10^a. These edges are secured in position by screws 24.

Thus the condenser 15 is arranged in a space formed by wall 10^a and wall member 21 and is spaced therefrom by bars 16 and 85 17 so that currents of air can pass upwardly and around the condenser coils. The circulation of air through this space, which is open both at the top and bottom, increases 90 the condensing qualities of the condenser.

The lower end of the condenser is connected to a cap 25 which is screwed on one end of a tubular member or reservoir 26, the opposite end of which is closed by a cap 27 having a valve fitting 28 connected by a pipe 95 29 to the inlet end of the cooling or expansion coil 12.

A strainer 30 is fixed to cap 25 by means of a ring 31 which engages the annular edge of the strainer and is secured to the cap by 100 rivets 32. The refrigerant fluid delivered to the reservoir by the condenser passes through said strainer which catches and retains any foreign material and prevents it from circulating through the system. Tubular member 26 is preferably disposed under the bottom wall 10^b of the refrigerator and is supported in position by straps 34 which are fixed to wall 10^b. Member 26 is of suitable 105 dimensions to hold a supply of refrigerant 110

so that the cooling or expansion coil is at all times assured of a uniform and steady supply thereof.

A discharge valve 14^a is interposed between compressor 14 and condenser 15 and controls the communication therebetween so that said condenser may be disconnected from the compressor by shutting said valve and can also be disconnected from the expansion coil by shutting the valve located in valve fitting 28.

In the modified form shown in Figure 9, the side walls of refrigerator 10 are extended rearwardly past the rear wall 10^a as indicated at 10^c and form a vertically disposed recess or chamber open at the top and bottom and adapted to receive the condenser coil 15. This recess is closed by an auxiliary rear wall 35 which rests against the edges of extensions 10^c.

In the form shown in Figure 10, a box-shaped structure 36, open at top and bottom and containing condenser coil 15, is fitted against the rear wall 10^a of refrigerator 10.

I claim:

The combination of a refrigerator having

its rear wall provided with a vertically disposed chamber open at top and bottom to the atmosphere, a compressor arranged on top of said refrigerator, an expansion coil arranged within and supported by said refrigerator, a condenser coil arranged in said chamber and having horizontally disposed convolutions arranged in superposed relation in a vertical plane, said condenser being co-extensive with said chamber, one end of said condenser being connected to the high pressure side of said compressor, said condenser being spaced from the walls of said chamber whereby air is induced to circulate freely around said condenser coils and through said chamber by the thermal conditions prevailing in said chamber, and a refrigerant reservoir secured to said refrigerator below said condenser and connected to the lower end thereof and having its opposite end adapted to be connected to the expansion coil of the refrigerator.

In testimony whereof I hereunto affix my signature this 16th day of December, 1924.

JOHN O. CARREY
